UNITED STATES PATENT OFFICE.

JOHN CHARLES TELFORD, OF STOURBRIDGE, ENGLAND.

BUILDING CONSTRUCTION.

Application filed January 13, 1926, Serial No. 81,054, and in Great Britain December 4, 1924.

This invention relates to a new or improved method of and means for house and other building construction, and refers particularly to a construction in which metal, 5 preferably steel, is employed as a building material.

The object of my invention is to provide an improved method of metal building construction whereby an ordinary dwelling 10 house or like building can be rapidly and cheaply erected on any desired site from standard parts, every step in the erection from foundations to roof avoiding so far as possible brick-laying, plastering, or carpentering.

A further object of my invention is to provide a method of building construction in which the use of uprights or stanchions to take the weight of the structure and provide the necessary stiffness and rigidity for the walls is rendered superfluous, these functions being performed by the flanges of the panels of which the wall is built up. The individual units or parts of the building 25 can be readily turned out in large quantities, and when delivered on the site may be assembled and the building erected in very much less time than hitherto and probably with a reduction in the capital cost of a 30 house or other building.

According to my invention, the walls of a house or other building are formed from metal plates of storey height, flanged on all edges, which are assembled without uprights 35 or columns and with the vertical flanges of adjacent plates directly abutting and inwardly directed, and the plates are secured together by bolts or the like passing through the flanges. The bottom flanges of the 40 lowermost row of plates are preferably bolted directly to a concrete or other foundation and the walls are carried to the desired height by superimposing plates upon 45 each other in vertical alignment. The roof is preferably formed of similar plates, red-lead or other caulking being placed between the flanges of adjacent plates, and the ridge of the roof is formed by curved or other shaped flanged plates whose side flanges are 50 bolted to the adjacent flanges of the roof plates.

Guttering is provided along the eaves to carry off rain, and this may conveniently be bolted to the upper plates of the walls.

By the use of these flanged plates the necessary stiffness and rigidity for the walls and roof is in the plates themselves, and vertical girders or other struts or columns are unnecessary. This feature has the further advantage that interior or partition 55 walls can be placed in any desired position, so that a house of standard external dimensions can be divided up as desired by the prospective purchaser or tenant. The steel plates forming the walls are standardized, 60 and for a bungalow or cottage each plate extends for the full height of the walls, the width of the plates being one third to one half of their height.

In a house of two storeys the walls are 65 formed of two rows of superimposed plates which may be bolted directly together, or a shorter plate may be interposed projecting slightly beyond the plane of the main plates to form a union or expansion member between 70 two series of main plates and to form a plinth course at half the height of the wall.

The lining of the building is preferably 75 in sheets or panels of asbestos or the like also of standardized dimensions, so that it can be supplied from the works ready to assemble.

A complete house could thus be supplied to a site and erected in a few days with a 80 minimum amount of labour. When completed the walls and roof of the house may be painted externally as desired, and the roof may, if desired, be covered with tiles or any other suitable covering material 85 though this is unnecessary except from the point of view of appearance. The internal and external design and lay-out of the house may vary within wide limits according to the desires of the prospective owner or 90 tenant.

As an example of our improved construction a pair of semi-detached two-storey houses constructed in accordance with my invention have been illustrated in the accompanying drawings in which:—

Figure 1 is a perspective view of a part of one of the steel plates which form the main building units.

Figure 2 is a front elevation of the pair 105 of houses.

Figure 3 is a vertical section through one wall and the roof of one house.

2
Figure 4 is a plan of the roof for the pair of houses.

Figure 5 is a vertical section showing the arrangement of the partition walls and doors.

Figure 6 is a horizontal section on the line 6—6 of Figure 5.

Figure 7 is a plan on an enlarged scale showing the arrangement of the main ridge members of the roof.

As shown in Figure 1 the main building unit in the construction of a house or other building in accordance with my invention is a steel plate 1, flanged on all four edges. 15 These plates are conveniently produced by pressing from sheet steel between suitable dies, the metal at the meeting corners of the flanges 2 being slit if desired, though this is not necessary unless the plates are of considerable thickness.

The vertical height of each plate is substantially that of one floor of the building and the width of the plate is preferably one third to one half of its height.

25 These plates together with all the other component parts of the house are standardized units so that the whole of the material can be supplied to the site and assembled in a very short time by unskilled or semi-skilled labour, the house being ready for occupation immediately on completion.

The foundation must, however, be prepared first, and this consists of a concrete or other raft or bed 3 of suitable dimensions, 35 and preferably of greater depth below the outer and party walls of the house as shown at 4. Set in the concrete at intervals are rag-bolts 5 by which the flanges of the lowest row of plates 1 are secured to the foundation, and by the use of a template strip or strips the position of these bolts can be accurately fixed. The plates 1 are then erected in position to form the outer walls, the lower flange of each being secured to 40 the foundation by the rag-bolts 5, while the meeting vertical flanges of adjacent plates are bolted together, a coating of red lead or the like preferably being placed between to prevent corrosion. To the upper flanges 45 of the plates is secured a horizontal flanged or channel member 6, as shown in Figure 3, which projects outwardly beyond the plates 1 and serves firstly to form a plinth course which breaks the severe line of the wall, 50 secondly to form a jointing member capable of slight distortion to allow for vertical expansion and contraction of the walls under changes of temperature, and thirdly to receive the ends of the joists carrying 55 the floors for the upper storey.

The next row of plates forming the walls of the upper storey is secured to the upper flange of the member 6, and the roof is secured to the upper edges of these plates.

60 The main members of the roof consist of

a member 7 of inverted channel section which forms the ridge of the roof and similar members 8 which form the hip rafters. The junction between the members 7 and 8 is made by castings or pressings 9 of Y-shape 70 in plan, as shown in Figure 7 to which the members 7 and 8 are secured, and channel section members 10 secured to the corners of the walls receive the outer ends of the members 8. The structure so formed can be 75 placed in position and the roof is completed by flanged steel plates 11 similar to the wall plates and bolted to each other and to the members 7 and 8, as shown in Figure 3, as soon as the outer walls are completed, so 80 that the remainder of the work is carried out under cover and is not interfered with by weather conditions. The floors of the upper rooms are supported by joists 12 which are carried across the full width of 85 the building, and their outer ends rest upon and are carried by the lower flanges of the members 6 as shown in Figure 3. These joists are preferably of the fitch plate type, that is a steel plate with a wooden beam on 90 each side connected by bolts, as this gives a very strong joist without excessive weight. The flooring for the upper storey consists of boards 13 nailed to the joists, while the flooring on the ground floor consists of 95 boards 14 laid directly on the concrete foundation or nailed to battens laid edgewise in the concrete, the underside of the boards being creosoted or otherwise treated against damp.

100 The interior surface of the outer and party walls of the house is formed by asbestos or other sheets 15 which are secured to wooden strips 16 supported by short angle pieces 17 bolted to the flanges of the plates 1 as shown in Figure 5. These sheets are 105 preferably of the same dimensions as the plates 1, and the vertical junctions between the sheets are covered by wooden fillets 18 so that a pleasing panelled effect is produced.

110 Skirting boards 19 and cornices 20 are nailed through the sheets to the strips 16 below, and a wooden moulding 21 is preferably secured in each corner of a room as shown in Figure 6 to eliminate angles which 115 would harbour dust.

Figure 6 also illustrates the method of completing the exterior corner of each wall by means of a flanged member 22 of substantially quadrant section which is bolted to the 120 flanges of the end plates in each wall.

The interior partition walls between rooms may be placed in any desired position to suit the purchaser or tenant, and consist of asbestos or other sheeting 23 secured on opposite sides of wooden strips 24 as shown in Figure 5. A substantially sound-proof wall is thus produced. Doors and windows are hung between posts 25 secured to the flanges of the plates 1 as shown in 125

Figure 6. Other minor details of the interior construction of the house need not be entered into as they will be readily apparent to anyone familiar with building construction. Where a number of houses of standard type are under erection as in a town-planning scheme, the pipes for water, gas, and other fittings may be supplied secured in place upon the appropriate wall plates so that it is only necessary to connect the sections of piping together in the course of erection.

The wall plates 1 are preferably supplied coated on the inner surface with a suitable bituminous or other paint and after erection the outer surfaces of the walls and roof are painted or finished in any desired manner. Rust or corrosion can be entirely prevented by painting at regular intervals so that the durability of a house constructed in accordance with my invention should be at least equal to that of a brick house, while the maintenance charges will be low.

I claim:

1. A building having more than one 25 storey and having the walls of each storey formed by a row of metal plates flanged on all four sides, in combination with means for securing directly together the vertical flanges of adjacent plates, and a horizontal 30 channel member connecting the rows of plates between floors and forming a plinth course, said member being adapted to be distorted slightly to allow for vertical expansion and contraction of the walls under 35 changes of temperature.

2. A building having more than one storey and having the walls of each storey formed by a row of metal plates flanged on all four sides in combination with a horizontal 40 channel member connecting two rows of plates between floors and joists to carry an upper floor supported by their ends which enter said horizontal channel member.

In testimony whereof I affix my signature.
JOHN CHARLES TELFORD.
